UNITED STATES PATENT OFFICE

149,955

DESIGN FOR A LIP ROUGE APPLICATOR
OR THE LIKE

Ralph E. Kruck, Clinton, Conn.

Application April 14, 1947, Serial No. 138,373

Term of patent 14 years

(Cl. D86—10)

To all whom it may concern:

Be it known that I, Ralph E. Kruck, a citizen of the United States, residing at Clinton, in the county of Middlesex and State of Connecticut, have invented a new, original, and ornamental Design for a Lip Rouge Applicator or the like, of which the following is a specification, reference being had to the accompanying drawing, forming part thereof.

Fig. 1 is a front elevational view of a lip rouge applicator showing my new design;

Fig. 2 is a side elevational view of the lip rouge applicator shown in Fig. 1;

Fig. 3 is a sectional view on the line 3—3 of Fig. 1 and

Fig. 4 is a plan view of the bottom of the applicator.

I claim:

The ornamental design for a lip rouge applicator or the like, as shown.

RALPH E. KRUCK.
